CLAIM

We claim the ornamental design for a finisher for multi-function printer, as shown and described.

DESCRIPTION

FIG. 1 is a top, front and right side perspective view of a finisher for multi-function printer showing our new design; FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is a top, front and left side perspective view thereof.

The broken lines in the figures show portions of the finisher for multi-function printer which form no part of the claimed design.
